UNITED STATES PATENT OFFICE.

ROBERT C. STEVENS, OF ERIE, PENNSYLVANIA, ASSIGNOR TO SKINNER ENGINE COMPANY, OF ERIE, PENNSYLVANIA, A CORPORATION OF PENNSYLVANIA.

STEAM-ENGINE.

1,112,489.

Specification of Letters Patent.

Patented Oct. 6, 1914.

Application filed March 29, 1913. Serial No. 757,528.

To all whom it may concern:

Be it known that I, ROBERT C. STEVENS, a citizen of the United States, residing at Erie, in the county of Erie and State of Pennsylvania, have invented certain new and useful Improvements in Steam-Engines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to steam-engines of the type known as central exhaust engine, and has for its object the provision of an exhaust valve in the piston body, which is adapted to open when the central exhaust 20 ports have been uncovered by the piston and to be automatically closed by reason of the compression accumulating behind the piston upon its return stroke, when said piston has traveled a certain portion of said 25 return stroke.

The features of my invention are herein-after set forth and explained and are illustrated in the accompanying drawings in which:—

30 Figure 1, is a longitudinal section on the line $x-x$ in Fig. 2, looking in the direction of the arrow v , of an engine cylinder and piston embodying my invention. Fig. 2, is a transverse section thereof, on the line $y-y$, 35 in Fig. 1 looking in the direction of the arrow in Fig. 1. Fig. 3, is a longitudinal section of the cylinder and a section of the piston, on the line $z-z$, in Fig. 2, looking in the direction of the arrow w , in Fig. 2. Fig. 40 4, is a longitudinal section showing an alternative construction of my invention. Fig. 5, is a view in central horizontal section of Fig. 2, of the engine cylinder showing the engine piston in elevation therein 45 looking upward at the inside thereof.

In these drawings, A, indicates an engine cylinder having central exhaust ports, B.

C, indicates a piston in said cylinder; C', 50 indicates a piston-rod. Within the piston C, I place removable sleeves D, which sleeves are divided by the transverse wall d ; upon which wall, d , there is a valve-stem support d' . The sleeves D, have an out-turned flange d^2 , on one end thereof, which

engage an annular shoulder d^3 , in the body of the piston C. The sleeves D, are secured in place in the piston C, by means of screw plugs D', which also close one end of said sleeves D; the other end of the sleeves D, are closed by means of a puppet-valve E, which has a valve-stem E', mounted in and supported by the valve-stem support d' , hereinbefore described. Secured upon the end of the valve-stem E', are pistons F, which preferably operate in the sleeves D, between the transverse division wall d , and the plugs D'. Between the division walls d , and the valves E, I place springs G, which normally maintain the valves E, in an open position.

Leading inwardly from the end of the piston C, there is a steam passage H, (see Fig. 3), which terminates in the small piston chamber formed by the sleeve D, and the division wall d , and the plug D', through which passage compressed air in the cylinder A, and steam may enter into said small piston chamber and operate upon the small piston F, therein, to close the valve E, and maintain said valve E, in a closed position until the pressure in the cylinder A, is relieved by the uncovering of the central exhaust ports B, by the piston C. In the side of the piston C, I make segmental recesses J, one of which is shown in full lines in Figs. 2 and 3, and are indicated by broken lines in Figs. 1, 2 and 3. Referring to Fig. 1, it will be seen that the segmental recesses J, are staggered. From the chamber immediately behind each of the valves E, an exhaust port K, leads into the segmental recess J, and from each of said chambers an exhaust duct L, leads into the chamber of the opposite small piston F.

It will be noticed that both of the sleeves D, can be removed from the piston C, by removing the cylinder-head A', without removing the piston C, from the cylinder A, so that I am thereby able to remove and replace the said sleeves D, and the valve-mechanism mounted therein, when desired. In operation, when steam is introduced into the end A^2 , of the cylinder A, the pressure thereof enters into the passage H, and forces the piston F, backward, which action of the piston F, closes the valve E, and compresses the spring G, and at the same time said piston covers the end of the exhaust opening L, thereby forming an air cushion

between the piston F, and the plug D'. Meanwhile the piston C, travels backward toward the end A³, of the cylinder A, and at a point near where the central exhaust 5 ports B, are uncovered by the piston C, the pressure in the end A², of the cylinder A, will be relieved, which also relieves the pressure on the piston F, through the passage H, and permits the spring G, to open the 10 valve E, so that on the return of the piston C, toward the end A², of the cylinder A, steam may pass freely through the casing D, passage K, and segmental chamber J, until the end j, of said chamber, has passed 15 the point, b, of the central exhaust port B, when compression in the end A², of the cylinder A, will begin to accumulate until the intensity thereof is sufficient to act upon the piston F, through the passage H, to 20 compress the spring G, and close the valve E, when said valve will be retained in a closed position until the central exhaust ports B, are again uncovered, or nearly so. The action of both the valves shown in the 25 piston, is identical, one valve operating from the end A², of the cylinder, and the other valve operating from the end A³, of the cylinder.

In the construction shown in Fig. 4, the 30 spring G, for opening the valve E, is dispensed with, and the exhaust passage L, from the chamber of the piston F, is not used, and in lieu thereof the piston F, is provided with a steam passage, M, leading 35 from the chamber of the piston F, to the end A³, of the cylinder A.

The operation of the construction shown 40 in Fig. 4, is as follows, viz:—When the piston C, travels backward toward the end A³, of the cylinder A, the pressure in the end A², gradually decreases until the central 45 ports B, are uncovered, during which time the pressure in the end A³, communicated through the passage M, to the chamber of the piston F, has increased until the intensity thereof is sufficient to cause the piston F, to open the valve E, and hold it open until the piston C, has traveled backward toward the end A², of the cylinder A, to 50 reduce the pressure in the end A³, of the cylinder A, and to increase the pressure in the end A², of the cylinder A, communicated through the steam passage H, in the piston C, to the chamber of the piston F, sufficient 55 to cause said piston F, to close the valve E, and maintain it in a closed position until the piston C, has again uncovered the central exhaust ports B, or nearly uncovered them. In all other respects the operation 60 of the construction shown in Fig. 4, is the same as that shown in Figs. 1, 2 and 3.

From the foregoing description and the drawings, it will be obvious to those skilled in the art, that by the use of my invention, 65 I can construct a "uniflow" non-condens-

ing engine, that is, an engine in which the steam flows continuously from the ends of the cylinder toward the central exhaust ports, without the employment of mechanically actuated gear for operating exhaust 70 valves.

Therefore having fully shown and described my invention, so as to enable others to construct and operate the same, what I claim as new, and desire to secure by Letters-Patent of the United States, is:—

1. The combination with a steam engine cylinder having central exhaust ports, of a piston in said cylinder having exhaust passages therein adapted to communicate 80 with said central exhaust ports, a valve in said piston controlling the exhaust to said ports, and means within said piston actuated by pressure within the cylinder for controlling said valve during the compression and admission periods, substantially as set forth.

2. The combination with a steam engine cylinder having central exhaust ports, of a piston in said cylinder having passages 90 adapted to communicate with said central exhaust ports, a valve in said piston adapted to control the exhaust through said passages to said ports, means within said piston to open said valve during the exhaust period 95 of each stroke, and means within the piston actuated by pressure within the cylinder for closing said valve during the compression and admission period, substantially as set forth.

3. In a steam engine, a cylinder having central exhaust ports, an engine-piston in said cylinder having steam passage-ways and valve and piston chambers therein adapted to communicate with said central 105 exhaust during the reciprocation of said engine-piston and with the interior of said cylinder, a valve adapted to close said valve-chamber, a valve-stem thereon, a piston in said piston-chamber secured on said valve-stem, adapted to be actuated by fluid in that end of said cylinder toward which said engine-piston is moving to cause said valve to close the passage through said valve-chamber and retain it in a closed position 110 until the central exhaust ports in said cylinder are uncovered by the engine-piston on its return stroke and means contained within said engine piston to operate said valve in the opposite direction, substantially as set 115 forth.

4. In a steam-engine, a cylinder having central exhaust ports, an engine-piston therein adapted to cover and uncover said ports during its reciprocation having a 125 valve-chamber and steam passage-ways therein adapted to communicate with said central exhaust during the reciprocation of said engine-piston, and a piston-chamber and other steam passage-ways therein in 130

- constant communication with the interior of said cylinder and said piston-chamber and said central exhaust, a valve adapted to close communication between the interior of 5 said cylinder and said valve-chamber, a valve-stem thereon, a piston in said piston-chamber secured on said valve-stem and adapted to be actuated by fluid in that end of the cylinder toward which the piston is 10 moving, communicated thereto through some of the steam passages to operate said valve to close communication between said end of the cylinder and the valve-chamber in said engine-piston, and mechanism con- 15 tinued within said engine piston adapted to operate said valve in the opposite direction when said central exhaust ports are uncovered on the return stroke of said piston, substantially as set forth.
- 20 5. In a steam engine, a cylinder having central exhaust ports, an engine-piston therein adapted to cover and uncover said central exhaust ports during its reciprocations, having therein a valve-chamber in 25 said engine-piston, a depressed recess in the periphery of said piston, an exhaust port extending between said valve-chamber and said depressed recess, a piston chamber, a steam passage-way leading from one end of 30 said engine-piston to one end of said piston-chamber, and another passage-way leading from the opposite end of said piston-chamber to said central exhaust; a valve mounted in said engine-piston, a valve-stem 35 thereon, a piston in said piston-chamber and secured on said valve-stem adapted to be actuated by fluid in said cylinder to cause
- 40 said valve to close communication between the interior of said cylinder and the valve-chamber in said engine-piston and retain 45 said valve in a closed position until said central exhaust ports are uncovered by the return stroke of said engine-piston, and means to move said valve in the opposite direction, substantially as set forth.
6. In a steam-engine, a cylinder having central exhaust ports, a piston therein adapted to cover and uncover said central exhaust ports during the reciprocations thereof, having a longitudinal chamber 50 therein, a steam passage-way leading from the end of said piston into said chamber and a passage-way communicating between said chamber and said central exhaust, a sleeve secured in said chamber having the inner 55 end thereof closed and a valve-seat opening in the outer end and a valve-stem opening in the closed inner end thereof, a valve seated upon said valve-seat opening, a valve-stem thereon and extending into said piston 60 chamber, a piston in said piston-chamber secured on said valve-stem, said engine-piston having a depressed recess in its periphery and an auxiliary exhaust port extending therefrom into said sleeve, and spring 65 mechanism adapted to open said valve when there is no pressure in that end of the cylinder, substantially as set forth.

In testimony whereof I affix my signature, in presence of two witnesses.
